PENNSYLVANIA, A CORPORATION OF VIRGINIA.

MOLD-DIMENSIONING MECHANISM FOR TYPE-MACHINES.

SPECIFICATION forming part of Letters Patent No. 770,253, dated September 20, 1904.

Application filed January 30, 1904. Serial No. 191,382. (No model.)

To all whom it may concern:

Be it known that I, JOHN SELLERS BANCROFT, of Philadelphia, in the county of Philadelphia, State of Pennsylvania, have invented 5 certain new and useful Improvements in Mold-Dimensioning Mechanism for Type-Machines; and I do hereby declare the following to be a full, clear, and exact description of the same, reference being had to the accompanying 10 drawings, forming a part of this specification, and the figures of reference marked thereon.

This invention relates to improvements in or upon the class of type-casting machines represented in Patent No. 625,998, wherein 15 the dimensioning of the mold is effected through the medium of the die-case-centering mechanism and the maximum number of sizes is limited to the number of rows or columns of matrices contained in the die-case; and it 20 has for its principal object to render the dimensioning of the mold independent of the movements of the die-case and of the position of the matrices therein, so that a larger number of sizes or a more extended range of adjustment may be provided and the matrices 25 arranged in any desired order without reference to their space value.

To this end the invention consists in providing the mold-adjusting devices with a control or adjusting system separate from and 30 independent of the die-case-centering mechanism and under the direct control of the record-strip, the latter being provided with a special dimensioning perforation or signal in addition to the die-case-locating perforations or 35 signal, so that the number of sizes and their relative dimensions are dependent solely upon the capacity of the mold-adjusting devices and is not limited or otherwise controlled by 40 the number or position of the matrices in the die-case, all as hereinafter more fully described, the novel features being pointed out in the claims.

In the accompanying drawings, illustrating 45 a preferred form of embodiment, Figure 1 is a top plan view of a casting-machine, showing the application of the mold-adjusting mechanism thereto. Fig. 2 is a top plan view of the

attachment on an enlarged scale. Fig. 3 is an end elevation, partly in section, to show 50 the arrangement of the stop-pins or primary controller. Fig. 4 is an end elevation, partly in section, to show the construction of the spring-box. Fig. 5 is a sectional view illustrating the manner of supporting the jaws 55 for shifting the normal wedge. Fig. 6 is a perspective view of the wedge-shifting jaws.

Like numerals in the several figures designate corresponding parts.

The type-casting machine illustrated and 60 to which the present embodiment of the invention is specially adapted, other forms being admissible, is that of Patent No. 625,998, to which reference may be had for a more detailed description of its construction and 65 operation, the general arrangement of its principal elements being shown in Fig. 1.

It is deemed sufficient for present purposes to state that in the prior machine the normal wedge 132 and the justification-wedges 141 70 and 142 for varying the dimensions of the mold-cavity were shifted and their positions determined by oppositely-moving jaws 136, attached to and moving in unison with the jaws of the secondary controlling or positioning mechanism. Hence the permissible number of 75 adjustments was limited to the number of rows of matrices in the die-case—*i. e.*, fifteen—and the unit of adjustment was determined or limited by the interval between the centers of adjacent matrices as measured upon the wedges or other adjusting media.

According to the present scheme the movements of adjustment instead of being derived from the die-case-centering mechanism, as 85 heretofore, are effected through a separate mechanism controlled directly by the record-strip and operating independently thereof to shift the mold-adjusting devices to any one of a series of positions representing different 90 degrees of adjustment, and in the adaptation shown with a view to insuring complete harmony of action as between the correlated mechanisms this new adjusting and control mechanism is connected to the same jaws 136 95 which heretofore effected the shift of the

wedges, to which end said jaws are disconnected from those of the secondary positioning mechanism and provided with independent guides, as seen in Fig. 5. This separation of the jaws 136 from the adjusting mechanism of the die-case is designed, primarily, to remove the normal mold-adjusting devices, such as the normal wedge, from the direct control of said die-case-adjusting devices, so that the dimensioning of the mold may be independently effected, and the same result might be obtained by simply removing said normal mold-adjusting devices from the sphere of action of the jaws of the secondary positioning mechanism, as by removing the projection on the normal wedge from between the jaws and providing a duplicate set of jaws 136 in operative relation to the normal wedge or other normal mold-adjusting devices, in which case one set of jaws would operate, as heretofore, upon the justification devices, while the other set acted upon the normal mold-dimensioning devices.

Aside from the fact that the jaws 136, as herein shown, are independent of the secondary positioning mechanism of the die-case, hence are subject to independent control, their action with relation to the wedges 132, 141, and 142 is in no wise changed or affected.

The new adjustment-controlling mechanism is supported upon a frame 1, either formed integral with or attached to the main frame in rear of the wedges. Upon this frame is erected a primary controller in the form of a plurality of separately-movable pins 2, serially disposed in fixed relation, a primary positioning or gaging mechanism in the form of oppositely-moving jaws 3, the latter cooperating with any one of the pins 2 when projected to determine the closed position, a secondary controller or shiftable gage in the form of a stop-bar 4, the latter acted upon by the jaws 3 to bring it to the position designated by pin 2, and a secondary positioning or gaging mechanism in the form of oppositely-moving jaws 5, alternating as to direction of movement with jaws 3 and contacting on stop-bar 4 to determine their closed position, each of said jaws 5 being connected by a translating device, such as rod 6, with one of the wedge-shifting jaws 136.

Each pin 2 works through a guide-plate 7 and is provided with a retracting-spring 8 and a piston 9, the latter working in a cylinder 10, formed in block 11, secured to frame 1. A pipe 12 leads from each cylinder 10 to one of the ports in the paper-feed mechanism, so that each pin is under the control of perforations located in the line of its inlet-port.

The jaws 3 and 5 are guided to reciprocate above the series of pins 2 upon parallel rods 13, supported in brackets 14 at the opposite ends of block 11, said brackets forming stops for the jaws during their opening motions.

The devices for communicating motion to

the jaws 3 comprise a pair of levers 14, each pivotally connected at one end to one of the jaws and having their opposite ends joined together by an adjustable link 15. One of the levers 14 is pivotally attached by a link 16 to the frame 1, and the other is in like manner coupled by a link 17 with an actuating-lever 18, pivoted on the frame. In like manner the jaws 5 are each pivotally connected to one end of a pair of levers 19, the opposite ends being coupled together by an adjustable link 20, and one lever 19 is connected by link 21 to the frame and the other by a link 22 to the actuating-lever 18. By this arrangement of parts the motion of lever 18 in either direction will cause the jaws of one set to approach and those of the other to separate, at the same time permitting the jaws of each set to close at any point within the limit of their traverse, so that when one jaw of a set is intercepted by a pin 2 or stop-bar 4 the other jaw will continue in motion until brought into contact with the for the time being stationary jaw.

The stop-bar 4 is guided to reciprocate parallel with the jaws and is furnished with teeth to receive the end of a locking-bolt 23, the latter serving to hold the stop-bar after it has been brought to position by jaws 3 and while being acted upon by jaws 5.

One only of the pair of jaws 3 is projected into the plane of the pins 2 when elevated, and in order that said jaw may be caused to advance first during the closing movement a spring 24 is connected to the lever of the opposite jaw, as through a lever and link 25.

The actuating-lever 18 derives its motions from the main actuating-lever 390 of the die-case-centering mechanism, the connection being made through a link 26, crank-arm 27, rock-shaft 28, crank-arm 29, and a novel form of elastic coupling provided with a frictional checking device for absorbing or neutralizing the reaction of the spring.

To the lever 18 is secured a crank-pin 30, preferably formed or provided with a spherical bearing located between two bearing-blocks 31 32.

The block 31 is screwed or otherwise secured in the end of a sleeve 33, the latter provided with elongated transverse openings for the passage of the crank-pin 30 and surrounding the opposite bearing-block 32. To the crank-arm 29 is pivotally attached one end of a sleeve 34, surrounding sleeve 33 and likewise provided with elongated transverse openings for crank-pin 30.

The end of sleeve 33 opposite its bearing-block 31 is closed, as by a screw-plug 35, and the adjacent end of sleeve 34 is in like manner closed, as by a screw-cap 36.

Inclines or wedging-faces 37 are formed upon the bearing-block 32, and a rod 38, secured to said block, extends longitudinally of the sleeve 33 and is projected through open-

ings in plug 35 and cap 36, said rod being furnished with adjustable nuts or equivalent retaining means engaging cap 36. Interposed between the interior surface of sleeve 33 and the wedging or inclined faces of block 32 are wedge-blocks 39, and between a collar or washer 40, engaging the bases of said wedge-blocks and the plug 35, is arranged a tensioning-spring 41. The function of this coupling is to permit of a slight degree of yield in the driving connections when the resistance of inertia is excessive and at the same time check and delay the reactionary effect incident to the release of the spring after compression. Spring 41 is under initial tension and is adjusted to resist maximum working pressures, so that under normal conditions it will hold the parts to working position without yielding. When, however, an abnormal degree of resistance is encountered, the spring will yield slightly, its pressure being transmitted through the wedge-blocks and developing a frictional resistance upon the surface of sleeve 33, so that when the resistance of the driven member diminishes the effective action or reaction of the compressed spring will in like manner be diminished as to its effect upon the driven member, a portion of the power stored up in the spring being expended and absorbed in overcoming the frictional resistance to motion of the wedging-surfaces. By the arrangement described this yielding under excessive resistance and dampening the spring during expansion are made effective during the motions of the lever 18 in either direction—that is, during the closing movements of both sets of jaws 3 and 5. Thus when the driving crank-arm 29 is moved to the right, Fig. 4, its motion is transmitted through sleeve 34 and rod 38 to the bearing-block 32 and from the latter to bearing-block 31 and lever 18 through wedge-blocks 39, sleeve 33, and spring 41. In the event excessive resistance to the movement of lever 18 is encountered spring 41 yields slightly and in so doing increases its pressure upon the wedge-blocks and the friction between the bearing-block 31 and sleeve 33. The excessive resistance to the motion of lever 18 having been reduced or overcome, the tendency of the spring to expand suddenly and drive the lever 18 forward is checked and its power diminished by reason of the fact that it is compelled to act through the wedging or frictional devices during expansion. When the crank-arm 29 moves to the left, its motion is transmitted to the bearing-block 31 through sleeves 33 and 34, spring 41, and wedges 39, and should the resistance encountered be excessive the spring will yield, so as to permit the wedge-blocks to slide upon the inner face of sleeve 33, and in expanding the spring must first overcome the frictional resistance as developed by the wedges before its stored energy

becomes effective upon lever 18 and the parts 65 connected thereto.

Locking-bolt 23 receives motion from the actuating-lever 58 of the centering pin or plunger through link 42 and lever 43, the latter engaging shoulders on the locking-bolt. 70 This lever 43 is fast on a shaft 44, carrying an arm 45, to which is attached the rod 393 for operating the locking-bolts of the die-case-centering mechanism, so that both sets of locking-bolts will operate in unison. 75

The mechanism illustrated represents an adaptation of the invention to a form of machine wherein the adjusting-wedges have a limited range of motion divided into equal periods representing successive increments of 80 space value, and provision is made whereby the number of periods is increased from fifteen to eighteen. It is obvious, however, that any desired number of periods may be provided for and the units correspondingly diminished, that the throw of the wedge can be increased, and that the space value of successive periods can be varied at will by a proper rearrangement of the stop-pins 2 to correspond with the succession of adjustments 90 desired. 85

In adapting the improvements described to the machine of the prior patent the only additional changes required are an increase in the number of ports and ducts forming part 95 of the control system and the addition of a space-measuring perforation to each type-designating perforation or set of perforations in the record-strip, so that as the latter passes through the paper-feed pressure will be admitted to the die-case-centering mechanism, as heretofore, to center the matrix, and at the same time pressure will be admitted to the cylinder 10 of the pin 2, representing the assigned space value of the type, and thus the 100 mold will be adjusted to suit the character or the justification-wedges set, as required. 105

Having thus described my invention, what I claim as new, and desire to secure by Letters Patent, is— 110

1. In a type-casting machine such as described provided with die-case-centering mechanism controlled from a record-strip and an adjustable mold, the combination with the mold adjusting or dimensioning devices of an 115 independent control mechanism therefor governed by the record-strip and comprising a primary controller, primary positioning mechanism, a secondary controller and secondary positioning devices, the latter operating upon 120 the mold-adjusting devices, to dimension the mold.

2. In a type-casting machine such as described, the combination with means for positioning the movable member of the mold, of 125 a shifting mechanism therefor independent of the die-case-centering mechanism and comprising serially-disposed stop-pins controlled

directly from the record-strip, a pair of oppositely-movable jaws, a stop-bar controlled as to position by said jaws, and a second pair of oppositely-movable jaws engaging the 5 stop-pin and operating to shift the mold-positioning devices.

3. In a type-casting machine such as described, the combination with means for dimensioning the mold, such as a normal wedge, 10 of a pair of oppositely-movable jaws independent of the die-case-centering mechanism, and an adjusting or positioning mechanism therefor controlled from the record-strip.

4. In a type-casting machine such as described, the combination with the normal and 15 justification wedges thereof, of a pair of oppositely-movable jaws for positioning said wedges and a control system for said jaws independent of the die-case-centering mechanism and adapted to be governed in its action 20 from the record-strip.

5. In a casting-machine such as described, the combination with the oppositely-reciprocatory primary and secondary positioning 25 mechanisms and the actuating member therefor, of a double-acting combined elastic and frictional coupling.

6. A double-acting frictional and elastic driving-coupling for the control mechanism 30 of mold-adjusting devices such as described, comprising the following elements, in combination, to wit, a bearing on the driven member; a frame or casing provided with a fixed bearing-block and a movable bearing-block 35 oppositely disposed relatively to and engaging the bearing of the driven member; wedge-blocks interposed between the movable bearing and its frame or casing; a spring interposed between said wedge-blocks and the casing or frame; a driving member provided with 40 means for engaging said casing or frame, to move it in one direction; and a rod connected to the movable bearing-block, said rod engaging the driving means when moved in a 45 direction opposite to that first mentioned.

7. The combination, to form a double-acting driving-coupling, such as described, for the adjusting or positioning mechanism of type-casting machines, of the following elements, to wit; a pin on the driven member; 50 a tubular member provided with a bearing-block engaging said pin; an oppositely-disposed bearing-block also engaging the pin, supported to reciprocate within the tubular member and provided with inclines and a connecting-rod extending longitudinally of said tubular member; wedge-blocks interposed between said movable bearing-block and the tubular member; a spring interposed between said wedge-blocks and said tubular member; 55 and an actuating device coupled to the driving member and interposed between the tubular member and a shoulder on said connecting-rod.

8. In a double-acting driving-coupling such 60 as described, for the adjusting or positioning mechanism of type-casting machines, the combination of the following elements, to wit; a pin on the driven member; a sleeve extending transversely of said pin, closed at one end 65 and provided with a bearing-block at the opposite end; a second bearing-block supported to reciprocate within the sleeve and engaging the pin, said block being provided with a rod extending longitudinally through the sleeve 70 and beyond the closed end thereof; wedge-blocks interposed between the inner surface of the sleeve and the movable bearing-block therein; a spring interposed between the wedge-blocks and the closed end of the sleeve; 75 an outer casing coupled at one end of the driving member and provided at the opposite end with a head or cross piece engaging one end of the sleeve and with a passage for the rod; and a nut or shoulder on said rod outside the head or cross piece of said casing. 80
